(57) **CLAIM**

The ornamental design for a storage drawer cart, as shown and described.

DESCRIPTION

FIG. 1 is a front, right and top perspective view of a storage drawer cart showing our new design;

FIG. 2 is a front, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a front, right and top perspective view of the storage drawer cart shown in another configuration; and,

FIG. 10 is a front, right and top perspective view of the storage drawer cart shown in another configuration.

The broken lines depict portions of the storage drawer cart that form no part of the claimed design.

1 Claim, 10 Drawing Sheets
